CLAIM

We claim the ornamental design for the reflective strip, as shown and described.

DESCRIPTION

FIGS. 1-7 are views of a first embodiment of a reflective strip, showing our new design.

FIG. 1 is a front view of the reflective strip.

FIG. 2 is a top view of the reflective strip.

FIG. 3 is a left side view of the reflective strip.

FIG. 4 is a right side view of the reflective strip.

FIG. 5 is a bottom view of the reflective strip.

FIG. 6 is a rear view of the reflective strip.

FIG. 7 is a perspective view of the reflective strip, shown in a folded position and attached to a representative pocket illustrated in broken lines.

FIGS. 8-14 illustrate a second embodiment of the reflective strip.

FIG. 8 is a front view of the reflective strip.

FIG. 9 is a top view of the reflective strip.

FIG. 10 is a left side view of the reflective strip.

FIG. 11 is a right side view of the reflective strip.

FIG. 12 is a bottom view of the reflective strip.

FIG. 13 is a rear view of the reflective strip; and,

FIG. 14 is a perspective view of the reflective strip, shown in a folded position and attached to a representative pocket illustrated in broken lines.

The broken lines shown in the drawings show unclaimed subject matter and form no part of the claimed design.
